J. GARLICK

SHUTTLE

Filed June 3, 1925.

WITNESS
Wm. Shell

UNITED STATES PATENT OFFICE.

JEW GARLICK, OF PATERSON, NEW JERSEY, ASSIGNOR OF ONE-HALF TO WILLIAM CLARKSON, OF PATERSON, NEW JERSEY.

SHUTTLE.

Application filed June 3, 1925. Serial No. 34,552.

This invention relates to means for securing wound packages on the spindles in shuttles. One object is to provide a securing means which is especially adapted for securing on such spindles the paper cops or tubes which are frequently used to form the cores of the packages. Another object is to construct means for securing wound packages on shuttle spindles so that the loaded 10 spindle will be firmly supported against lateral distortion or displacement in the shuttle.

In the drawing,

Fig. 1 is a plan of a shuttle embodying the invention in the preferred form;

Fig. 2 is a fragmentary plan partly in section, showing a paper cop in secured position and partly in section;

Fig. 3 is a side elevation, with the rear 20 wall of the shuttle broken away; and

Fig. 4 is a fragmentary plan of a shuttle embodying a modified form of the invention.

In the drawing, 1 designates the shuttle 25 body having the usual cavity 2 for the filling package formed with extension 3, or portion of reduced width, at one end thereof. 4 is the spindle, of usual construction (except as hereafter noted), pivoted at its 30 butt to move in a vertical plan on a pin 5 which traverses the cavity extension 3; 6 is the spindle spring which bears against the spindle butt and obtains the necessary support in order to be tensioned on the pins 7, 35 also traversing the cavity extension.

In Figs. 1 to 3 are shown two claw members 8. These are arranged in the cavity extension 3 one on each side of the spindle-butt and penetrated by pin 5, and their lateral faces 8^a are flat so as to bear squarely against the lateral flat surfaces of the spindle-butt and sides of said cavity-extension, between which they snugly fit. Each claw member has its claw proper 8^b projecting toward the other and this, the acting portion of each claw, has a bearing at 8^c against the side of the cavity 3; in short, the claw-proper of each claw member is in this example rigidly supported by the side of the shuttle against lateral displacement. The claw members are formed of some metal, preferably aluminum.

The spindle 4 when depressed extends between the points of the two claws-proper, and in the best form of the invention it is

provided with opposite recesses 4^a in a registry with them, as shown in Fig. 3. The claws-proper extend to points having sufficient proximity to the spindle when depressed so that when the tube 10 which is to 60 form the core of the filling package is on the spindle, such tube being of paper or other yielding material as usual, the material of the tube will be held by the claws proper pressed into the recesses 4^a; in short, the 65 spacing of the points of the claws-proper is less than the diameter of the tube. Thus the tube will be locked on the spindle, and the lock will furthermore be substantially positive if, as explained, the material of the tube 70 is held by the claws-proper pressed into the recesses 4^a, each side of each recess as seen in Fig. 2 affording in effect a shoulder or abutment around which the material of the 75 core is by the claw-proper held bent or deformed and so engaged with said abutment. There is the further important advantage, especially where the claws are rigid, as by being rigidly supported against lateral displacement by the sides of the shuttle body, 80 that the loaded spindle is firmly reinforced against lateral distortion, as in the handling incident to applying thereto and removing therefrom the cop tube, and is also held in its proper position centrally in the shuttle 85 notwithstanding any wear which may occur at the sides of its butt or the sides of the cavity extension. It will be understood that when the spindle is swung up on its pivot 5 the tube is clear of the claws, so that it may 90 be freely slipped on or removed from the spindle.

In Fig. 4, the construction is substantially the same as that shown in the first three figures excepting that the claws-proper in this case are unsupported by the sides of the shuttle body and are formed of metal (as steel) blades. These blades 9 forming the claws have flat portions 9^a which are fitted snugly between the flat sides of the spindle butt and the adjoining sides of the cavity extension, being penetrated by the pin 5, and claws-proper 9^b which are formed by bending the relatively inner ends of the blades 100 first outwardly and then inwardly toward each other. The extremities of the claws-proper are, as before, sufficiently close together so that when the spindle with the cop tube thereon is fully depressed said extremities are caused to press into the material of 105 110

the tube, forcing it because of its yielding nature into the recesses 4^a. In this case it depends on the stiffness of the material of the claws both to secure the grip on the tube and support the spindle against lateral distortion or displacement.

I am aware that it is common in this art to employ claws or jaws on each side of the spindle having acting ends projecting 10 toward each other and arranged to engage in a circumferential groove at the butt of the core, as the wooden quill of a wound package placed in the shuttle; but so far as I know it is new to construct the jaws or 15 claws so that their said acting ends will be spaced less than the diameter of the filling-package core, whereby when the core is placed on the spindle and the spindle is then depressed into the cavity the claws 20 must bite into or indent the core in order to accomplish the full depressing or housing of the spindle. Preferably, as indicated, the spindle has a recess 4^a opposite the extremity of each claw-proper so that the 25 yielding material of the core is forced into such recess and a lock, substantially positive in character, is formed between the core and spindle.

Having thus fully described my invention 30 what I claim and desire to secure by Letters Patent is:

1. In combination a shuttle body having a filling-package cavity, a spindle having its butt fulcrumed in the cavity on an axis traversing the same, a tubular filling-package core of yielding material on the spindle, the spindle having laterally thereof in respect to its plane of movability an abutment fac- 35 ing lengthwise of the spindle, and a claw arranged laterally of said plane and between one side of the spindle butt and the adjoining side of the cavity and having a claw- 40 proper projecting toward the spindle and holding the material of the core engaged with said abutment.

2. In combination, a shuttle body having a filling-package cavity, a spindle having its butt fulcrumed in the cavity on an axis traversing the same, a tubular filling pack- 45 age core of yielding material on the spindle, the spindle having a recess covered by the core and facing laterally with respect to the plane of movability of the spindle, and

a claw arranged laterally of said plane and between one side of the spindle butt and 55 the adjoining side of the cavity and having a claw-proper projecting toward, and holding the material of the core pressed into, said recess.

3. In combination, a shuttle body having 60 a filling-package cavity, a spindle having its butt fulcrumed in the cavity on an axis traversing the same, a tubular filling package core of yielding material on the spindle, the spindle having a recess covered by 65 the core and facing laterally with respect to the plane of movability of the spindle, and means in the shuttle body holding the material of the core pressed into said recess. 70

4. In combination, a shuttle body having 75 a filling-package cavity, a spindle having its butt fulcrumed in the cavity on an axis traversing the same, a tubular filling package core of yielding material on the spindle, the spindle having opposite lateral recesses covered by the core, and opposite means in the shuttle body holding the material of the core pressed into each recess. 80

5. In combination, a shuttle body having 85 a filling-package cavity, a spindle having its butt fulcrumed in the cavity on an axis traversing the same, a tubular filling package core of yielding material on the spindle, and a claw arranged at each side of the 90 spindle butt and between the same and the adjoining side of the cavity, each claw having a claw-proper projecting toward and arranged opposite the claw-proper of the other claw and biting into the material of 95 the core.

6. In combination, a shuttle body having a filling-package cavity, a spindle having its butt fulcrumed in the cavity on an axis traversing the same, a tubular filling package core of yielding material on the spindle, and a claw arranged at one side of the spindle butt and between the same and the adjoining side of the cavity and having a 100 claw-proper projecting toward and biting into the material of the core and bearing against the side of the cavity.

In testimony whereof I affix my signature.

JEW GARLICK.
